UNITED STATES PATENT OFFICE

111,997

DESIGN FOR A TOWEL RACK OR SIMILAR ARTICLE

Roy S. Sanford, Oakville, Conn., assignor to The Autoyre Company, Incorporated, Oakville, Conn., a corporation of Connecticut

Application February 28, 1938, Serial No. 75,472

Term of patent 7 years

To all whom it may concern:

Be it known that I, Roy S. Sanford, a citizen of the United States, residing at Oakville, in the county of Litchfield and State of Connecticut, have invented a new, original, and ornamental Design for a Towel Rack or Similar Article, of which the following is a specification, reference being had to the accompanying drawing, forming a part thereof.

Figure 1 is a top plan view of a towel rack showing my new design;

Fig. 2 is a front elevational view of the towel rack of Fig. 1; and

Fig. 3 is an end elevational view of Fig. 2.

The dominant features of my design consist in the provision of a plurality of arms of square cross section with opposed corners lying in vertical and horizontal planes and extending from cylindrical bearings offset with respect to the vertical plane of a bracket of polygonal contour, the free ends of the arms terminating in angularly upturned end portions having notches on the corners spaced from the tips thereof to form substantial spheres, as shown.

I claim:

The ornamental design for a towel rack or similar article, substantially as shown and described.

ROY S. SANFORD.
